CLAIM

The ornamental design for a tray for an indoor plant cultivator, as shown and described.

DESCRIPTION

FIG. 1 is a front perspective view of the tray for an indoor plant cultivator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective reference view shown with a plant cultivator and a pod with soil and seeds.

The portions of FIG. 8 drawn in evenly dashed broken lines show environmental structure only and form no part of the claimed design. The portions of FIG. 8 drawn in uneven dot-dash lines show instructional indicia and form no part of the claimed design.

1 Claim, 8 Drawing Sheets
